UNITED STATES PATENT OFFICE

108,710

DESIGN FOR AN ELECTRIC ARC WELDER

Clifford M. Akins, Minneapolis, Minn., assignor
to Marquette Manufacturing Co. Inc., Minne-
apolis, Minn., a corporation of Minnesota

Application October 4, 1937, Serial No. 71,956

Term of patent 7 years

To all whom it may concern:

Be it known that I, Clifford M. Akins, a citizen
of the United States and a resident of Minne-
apolis, in the county of Hennepin and State of
Minnesota, have invented a new, original, and
ornamental Design for an Electric Arc Welder,
of which the following is a specification, reference
being had to the accompanying drawing forming
part thereof.

Figure 1 is a perspective view of an electric
arc welder showing my new design; and

Figure 2 is a reverse perspective view thereof
on a reduced scale.

The dominant features of my design reside in
the portions shown by solid lines on the drawing.

I claim:

The ornamental design for an electric arc
welder substantially as shown and described.

CLIFFORD M. AKINS.
